DESIGN FOR A BOTTLE DECAPPER

Theodore H. Low, New Haven, and Harry Laylon,
Waterbury, Conn.; said Laylon assignor to said
Low

Application May 29, 1936, Serial No. 62,908

Term of patent 14 years

To all whom it may concern:

Be it known that we, Theodore H. Low, a citizen of the United States, residing at New Haven, in the county of New Haven and State of Connecticut, and Harry Laylon, a citizen of the United States, residing at Waterbury, in the county of New Haven and State of Connecticut, have invented a new, original, and ornamental Design for a Bottle Decapper, of which the following is a specification, reference being had to the accompanying drawing, forming part thereof.

Fig. 1 is a view in side elevation of a bottle decapper showing our design;

Fig. 2 is an edge view thereof; and
Fig. 3 is a perspective view thereof.

The design is characterized by a hooked top or head portion having a downwardly-extending bowed arm of gracefully-tapering form, the front and rear surfaces of said arm being respectively convexly curved and concavely curved.

We claim:

The ornamental design for a bottle decapper substantially as shown and described.

THEODORE H. LOW.
HARRY LAYLON.
